Primary Examiner — John R Yeh(74) *Attorney, Agent, or Firm* — Cantor Colburn LLP(57) **CLAIM**

The ornamental design for a washing machine, as shown and described.

DESCRIPTION

FIG. 1 is a front perspective view of a washing machine, showing our new design;
 FIG. 2 is a front view thereof;
 FIG. 3 is a rear view thereof;
 FIG. 4 is a left-side view thereof;
 FIG. 5 is a right-side view thereof;
 FIG. 6 is a top view thereof;
 FIG. 7 is a bottom view thereof;
 FIG. 8 is an enlarged view of the portion, '8' in FIG. 1; and
 FIG. 9 is an enlarged view of the portion, '9' in FIG. 6.
 The dot-dash broken lines encircling enlargement portions of the design form no part of the claimed design. The broken lines illustrating portions of the washing machine form no part of the claimed design.

1 Claim, 9 Drawing Sheets(56)
